UNITED STATES PATENT OFFICE.

EDWARD G. ERNST, OF CLEVELAND, OHIO.

PRINTING MECHANISM.

391,203.

Specification of Letters Patent. Patented May 2, 1911.

Application filed March 21, 1908, Serial No. 422,448. Renewed October 27, 1909. Serial No. 524,965.

To all whom it may concern:

Be it known that I, EDWARD G. ERNST, a citizen of the United States, residing at Cleveland, in the county of Cuyahoga and State of Ohio, have invented a certain new and useful Improvement in Printing Mechanism, of which the following is a full, clear, and exact description.

The entire invention, as hereinafter described, will be most useful in connection with machines adapted for printing circular letters which simulate type written letters. These machines as they have heretofore been constructed print the circular letters but do not print thereon the names and addresses of the various parties to whom they are to be sent; neither do they print such addresses on the envelops in which said letters are to be sent.

The object of this invention in its completeness is to provide a printing machine of the sort specified with means whereby as it prints the circular letters, it will print severally thereon the names and addresses of the parties to whom they are to be sent, and will in the same order print said names and addresses on envelops in which the letters are to be sent. But the invention is also adapted for use for printing the successive addresses on circular letters printed on another machine, and on the envelops therefor.

The drawings show two forms in which the invention may be embodied, both of which have been worked out with special reference to adapting the inventions to a well known circular letter printing machine without requiring much modification in the construction of that machine.

The invention consists in the combination of parts shown in the drawings and herein-after described and definitely set forth in the specification and claims.

In the drawings, Figure 1 is a front view partly in section of a duplicating machine equipped with the invention,—the parts being shown in the positions they occupy when the printing cylinder has been turned about one-quarter of a revolution from the position it occupies when it draws an address slug from the slug magazine. Fig. 2 is a right end view of the machine. Fig. 3 is a sectional view in the plane indicated by line 3—3 on Fig. 1. Figs. 2 and 3 show the cylinder in the position it occupies when it is about to draw an address slug from the slug

magazine. Fig. 4 is a view showing the printing cylinder in section in the plane indicated by line 4—4 on Fig. 1 and showing a right end view of the fixed cylinder B. This view shows the printing cylinder in the 60 position it occupies when printing the address on a letter. Fig. 5 is a sectional view in the plane indicated by line 5—5 on Fig. 1. Figs. 6 to 9, inclusive, show a modified embodiment of the invention,—Fig. 6 being a front elevation thereof with the slug magazine and slugs therein shown in section. Fig. 7 is a sectional view in the plane indicated by line 7 on Fig. 6. Fig. 8 is a right end view of the machine shown in Fig. 6; 70 and Fig. 9 is a front view of the right end of said machine. Fig. 10 is a sectional view in the plane of line 10 on Fig. 6. Figs. 7 to 10 show the mechanism when the printing cylinder has been turned about one-quarter of a revolution from its position when an address slug is drawn from the slug magazine. Fig. 11 is a bottom view of 75 an address slug adapted for use with the specific form of machine shown in Figs. 6 to 10; and Fig. 12 is a bottom view of a slug adapted for use with the other form of machine.

Referring now to the specific construction shown in Figs. 1 to 5, A represents a 85 rotatable hollow cylinder within which is a fixed concentric cylindrical drum B. In the specific embodiment shown, this drum B is fixed at one end to a standard F; and the cylinder A is rotatably supported by anti-friction bearings upon said drum. A concentric shaft H is rotatably supported in standard F', and in the drum B. The cylinder A is fixed to this shaft, as is also a 90 crank h, by which the cylinder may be turned.

In the surface of the cylinder A is a shallow depression a which extends through a short arc around the cylinder. At what may be called the rear end of this depression is an abrupt shoulder a', but the front end of this depression gradually rises to the plane of the surface of the cylinder. (See Fig. 3). The part of the cylinder A to the left of this depression is the address printing member 100 A', and the part to the right of said depression is the envelop printing member A"—a part which might be omitted if the machine were not organized for addressing envelops. 105 As before stated, this specific construction 110

was designed particularly with reference to its use in connection with a well known type of circular letter printing machine. The cylindrical member A' may, therefore, be provided with longitudinal dove tail grooves for the reception of properly arranged type, and be in that respect, as well as in some others, substantially like the said machine. But any suitable means may be provided for holding a properly arranged form of type upon the member A', or said member may have no means for this purpose. In the surface of member A' is also a longitudinal groove a², which communicates with the recess a. In the surface of the member A² is another similar groove a³, which also communicates with recess a and extends therefrom across member A² to the right end thereof. The rear walls of these two grooves are substantially right and left continuations of the abrupt rear wall a' of the recess a. The width of these grooves measured around the cylinder is equal to the width of the address slugs T which they are to receive and hold. The length of the groove a² is such as to permit each slug T to be moved into proper relation to the type form on the member A'. These slugs are to be stacked in a magazine K which is fixed above the plane of the recess a. The magazine has no bottom, wherefore, the bottom slug of the stack will rest upon the surface of the cylinder. Each slug has on its top surface printing characters which spell the name and mailing address of some party to whom a circular letter is to be sent; and also, preferably, the words "Dear sir" or "Gentlemen," as the case may be. The front and rear edges of these slugs are dove-tailed, and the front and rear edges of the grooves a² and a³ are correspondingly undercut. The lower surface of each of these slugs is fashioned to engage with the device by which the slug is moved lengthwise of the cylinder into and out of the grooves a², a³. The slugs adapted for use in the form of the machine now being described are shown in Fig. 12, and each has a hole in its bottom.

On the inside of cylinder A is a longitudinal slideway a⁴ for the reception of a slide D. A slot a⁵ establishes communication between this slideway and the grooves a², a³, and the recess a. A bar J is fitted in and extended radially through a hole in this slide and into the slot a⁵, through which it may project when required, as hereinafter described. The inner end of this bar has a ball-shaped head j, which lies in an undercut cam groove b in the drum B. The shape of this cam groove is substantially shown in Fig. 1. This groove, however, is deeper in a certain part of its length than in others, and when the head j reaches the deepened part of the groove the bar J is drawn inward so that it no longer projects above the bottom surface

of the recess a. It will be so withdrawn when the cylinder, in its rotation, is moving the recess a under the bottom slug in the magazine. It is evident that, as this is taking place, the stack of slugs in the magazine will move down slightly, because the lower slug will keep its place against the bottom surface of this gradually deepening recess a. When the rear shoulder a' of this recess comes against the rear side of this bottom slug, it will push it along carrying it beneath the lower edge of the magazine. In the bottom of the recess a is a spring dog a⁶ which is pressed outward by a light spring. The weight of the slugs will force this dog inward, but after it has passed from under the slug it will fly up in front of the bottom slug and thereafter serve as a guide for the front edge of said slug, when the slug is being moved lengthwise of the cylinder.

As the cylinder rotates from the position in which bar J is drawn inward as described, the cam groove b will resume its normal depth, and the bar J will be thrust outward so that its outer end will enter the hole t in the said slug. As the cylinder continues to rotate, the slide D will be moved to the left by the cam groove b, and thereby the slug will be moved to the left and carried into the groove a² to the proper position therein, where it will be when the cylinder has been turned to the printing position—that is to say, where it will pass the platen roll M. As the cylinder continues to rotate this slide will be moved to the right carrying the slug with it said slug moving out of groove a² across recess a and into the groove a³. When it reaches this position the cam groove b is deepened so as to withdraw the bar J inward, leaving the slug in the position referred to, where it will print during the next revolution of the cylinder on an envelop fed between it and the platen roll M'. As the cylinder A goes on to complete its revolution this slide D will be moved to the left and will be in the first position referred to when the revolution is completed, and will then take the next slug through the same path. It is evident, therefore, that a circular letter may be printed during each revolution, and so will an envelop, but the envelop printed by a certain slug will be printed in the revolution next following that in which the same slug prints the address on the associated letter. During the latter part of the second revolution, the slug which was used for printing the address on a letter will be pushed against the slug which was used for printing an envelop, and the latter slug will be pushed toward the end of the member A². The third slug to be used will push these two along and will push the first one out of the right end of groove a³ and entirely off of the member A². When the slugs are pushed out of the groove a³ they may be

dropped onto any suitable inclined receiver by which they may be led into suitable stacking devices.

In certain types of duplicating machines the type is not inked, but, instead, an inking ribbon is stretched over the type between it and the platen roll. The present invention is, as before stated, adapted to be used with such a machine, and O, O' in Fig. 4 10 represents the familiar ribbon rolls of the member A'. A ribbon P² is also provided to be used in connection with the envelop printing member A². If the slugs carry the words "Dear sir" or "Gentlemen", it is 15 not desirable that they should be printed on the envelop. In order that it may not be printed, it requires some arrangement of the inking ribbon other than that which has been heretofore employed. A suitable arrangement for this purpose is shown in Fig. 20 1, wherein the two ribbon spools P, P' are mounted on member A². Two wire deflectors S, S' are secured to the member, and the ribbon passing from spool P goes around 25 the deflector S and thence over all of the printed characters on the slug except the words "Dear sir" or "Gentlemen". Thence the ribbon goes around the deflector S' to the spool P'. It is evident that by this arrangement of the ribbon the words "Dear 30 sir" or "Gentlemen" will not be inked and will not, therefore, print on the envelop.

By the use of the described machine circular letters and associated envelopes bearing the proper address inscriptions may be 35 printed, and letters and envelopes delivered in stacks in corresponding order, so that the mailing clerk who puts the letters in the envelop will have simply to fold the top 40 letter and put it in the top envelop.

Figs. 6 to 10, inclusive, show a modified embodiment of the invention. It includes the fixed drum B and rotatable cylinder A carrying the address the printing member 45 A', and the envelop printing member A². At the place where the recess α is formed in the surface of cylinder A in the first described device, a hole α' is cut through the cylinder, which hole extends a little more 50 than one-quarter around the cylinder, and has its front edge beveled inward. The magazine is arranged over this part of the cylinder, and the slugs rest upon the cylinder until the cut out part thereof passes beneath the magazine, when they drop 55 through the said hole and thereafter rest upon the surface of the inner fixed drum B. Upon this drum is a cam shaped rib b² which engages in a central recess t' in the lower 60 surface of each slug. (See Fig. 11). As the cylinder A is turned the rear wall of the hole in the cylinder engages with the rear face of the slug and carries it around. The cam rib b² moves it lengthwise into the 65 grooves a¹², a¹³, which are likewise cut

through cylindrical members A', A². The cylinder B extends beyond the right end of the cylinder A a distance equal to the length of the slugs, and the cam rib is carried onto this extended portion about half way down 70 its front side. The slugs will fall off this end of the cam rib onto a suitable chute Q, by which they may be led to a magazine in which they will stack themselves in the same order in which they were in the magazine 75 from which they were drawn. In this embodiment of the invention a slightly different arrangement of inking ribbon for the envelop cylinder is desirable. Three deflectors are employed, and the ribbon spool 80 P' is mounted on member A² in line with and substantially at right angles to the ribbon spool P.

Any suitable friction reducing devices may be employed in the machines described,—especially for the purpose of reducing the friction incident to the movement of the slugs or the device which moves them. For example antifriction balls may be interposed between the slide D and its guideway 90 in the form of the invention first described. Or antifriction rollers a⁸ may be mounted in the cylinder A in such position that the rear edge of each slug may slide against them. (See Fig. 7.)

As before stated, it is quite evident that this invention may be embodied in a variety of specific forms, and the primary invention is not limited to either specific construction shown in the drawings and heretofore described.

The machine need not be organized for printing the circular letter, or type for printing such letter need not be secured on the printing drums. In that case the machine will print addresses on envelops and on letters printed in some other machine.

Having described my invention, I claim:

1. In a printing machine, the combination of a slug support, a slug magazine arranged above the support to embrace a pile of slugs of which the bottom slug rests upon said support, a rotatable type carrying member provided with means for holding an address slug, means for periodically withdrawing the lower slug from the magazine and moving it circumferentially with said rotatable member, and a cam device arranged circumferentially around the axis of said rotatable member and adapted to engage a 110 slug as it is withdrawn from said magazine and to move it longitudinally into the embrace of the holding means on the rotatable member, and to subsequently move said slug longitudinally in the reverse direction out of 115 the embrace of said holding means before the rotatable member has completed its cycle.

2. In a printing machine, the combination of a rotatable cylinder having in its surface a longitudinal slug holding recess which 120

extends to the end of the cylinder, a support adjacent to the end of said cylinder, means for periodically depositing a slug upon said support and for moving it concurrently with 5 the printing cylinder around the axis thereof, and means for simultaneously moving said slug longitudinally into the recess of the cylinder and then out again before the cylinder has completed one revolution.

10 3. In a printing machine, the combination of a movable member provided with means for holding an address slug, a second movable member which is also provided with means for holding an address slug, 15 and means for introducing an address slug into the embrace of the holding means of one member and for transferring said slug into the embrace of the holding means of the other member, and for finally withdrawing 20 said slug from the embrace of the last mentioned holding means.

4. In a printing machine, the combination of a movable member provided with means for holding an address slug, an envelop addressing member movable concurrently with the said member and being also provided with means for holding an address slug, and means for introducing an address slug into the embrace of the holding means 30 of the first mentioned member and for transferring said slug into the embrace of the holding means of the envelop addressing member.

5. In a printing machine, the combination of a movable member having a recess adapted to receive an address slug, a second member which is movable with the first member and which also has a recess which is aligned with the recess thereof, a support between 40 said members having a bottom and rear edge which are aligned with the bottoms and rear edges of said two recesses, means for depositing address slugs upon said support, and mechanism for moving each slug into 45 and out of the recess in the first member and into and out of the recess in the other movable member.

6. In a letter printing machine, the combination of a rotatable printing drum having 50 a longitudinal recess for the reception of an address slug, a fixed drum within said printing drum, a cam carried by said fixed drum, and means by which said cam will move a slug lengthwise of the printing drum into and out of the recess therein while the drum is rotating.

7. In a printing machine, the combination of a rotatable drum having extending from one end thereof a longitudinal recess for 60 the reception of an address slug, a curved slug support adjacent to the recessed end of that drum, the slug supporting surface adjacent to said recess being in the same plane with the bottom of said recess, an open bottom slug magazine fixed above said sup-

port, a shoulder carried by the printing drum for engaging with the bottom slug in said magazine to draw it out of the magazine and along with said moving drum, and means for moving said slug longitudinally 70 into and out of said recess while the drum is rotating.

8. The combination of a rotatable hollow cylinder having a letter printing drum at one end and an envelop printing drum at 75 the other and an intermediate recess, the letter printing drum having a longitudinal channel communicating with said recess and extending a suitable distance lengthwise of said drum, and the envelop printing drum 80 having a channel communicating with said recess and extending from one end of the drum to the other, a fixed drum within the rotatable cylinder provided with a cam, a slug holding magazine fixed above the plane 85 of the recess in said cylinder, and means whereby the lower address slug in said magazine will be moved from said recess into the channel therefor in the letter printing drum, and then in the reverse direction 90 across said recess into and through the channel therefor in the envelop printing drum.

9. The combination of a rotatable cylinder having a letter printing drum at one end and an envelop printing drum at the other 95 and a recessed portion between said drums, there being an abrupt shoulder at the rear end of said recess and there being in the letter printing drum a channel whose rear edge is aligned with the rear edge of said recess, and there being in the envelop printing drum a channel whose rear edge is also aligned with the rear edge of said recess and which extends from one end of said envelop printing drum to the other, an address-slug magazine fixed over the recessed part of said rotatable cylinder, and means whereby the bottom slug in said magazine will, when it is withdrawn from said magazine, be moved lengthwise of the cylinder 110 into the recess in the letter printing drum and then in the opposite direction into and through the recess in the envelop printing drum.

10. The combination of a rotatable cylinder having a letter printing drum at one end and an envelop printing drum at the other end and a recessed part between said drums, said recess being extended longitudinally into the letter printing drum and entirely across the envelop printing drum, a fixed drum within the rotatable cylinder provided with a cam groove, a magazine fixed above the recessed part of said cylinder, a longitudinal slide carried by the rotatable cylinder, an arm radially movable through said slide engaging at its inner end with said cam groove and adapted to engage at its outer end with the bottom slug.

11. The combination of a rotatable cylin- 130

- der having a letter printing drum at one end and an envelop printing drum at the other end and a recessed part between said drums, said recess being extended longitudinally as 5 a slug retaining channel into the letter printing drum and entirely across the envelop printing drum, and a longitudinal slot through the bottom of said recess, a fixed cylinder within the rotatable cylinder provided with an undercut cam groove, a magazine fixed above the recessed part of said cylinder, a longitudinal slide carried by the rotatable cylinder, an arm radially movable through said slide and having an enlarged 10 head which fits in said cam groove and adapted to engage at its outer end with the bottom slug, said cam groove being deepened in some parts whereby it may move said arm radially inward and outward.
- 10 12. The combination of a rotatable drum having a longitudinal slug holding recess in its surface, means for moving an address slug longitudinally into said recess, combined with two ribbon spools carried by said 15 cylinder, a ribbon wound thereon, and deflectors over which said ribbon passes and by which it is guided so as to cover only a part of the printing surface on the slug in said recess.
- 20 13. In a printing machine, the combination of a movable member having a slug guide extending across the same, means for periodically depositing a slug upon said member, and means for moving said slug along 25 said guide in one direction to a printing position on said member, and then in the opposite direction along said guide to another printing position, and then off said member.
- 30 14. In a printing machine, the combination of a movable member having a transverse guide-way adapted to receive an address slug, a second member which is movable with the first member and which 35 also has a guide-way for the address slug, a slug support between said members having also in its surface a guide-way for said slug, which guide-way connects and is aligned with the guide-way first mentioned, a slug 40 hopper fixed above the supporting member, means carried by the supporting member for withdrawing the lowest slug from said hopper, and mechanism for moving the slug so withdrawn first in one direction into the 45 guide-way of the first mentioned member and then in the opposite direction along the guide-way in the supporting member into the guide-way on the other movable member.
- 50 15. The combination of a type-form-carrying member on which is a transverse slug guideway, a slug hopper fixed over said member, means for periodically delivering the bottom slug in the hopper onto said member and into the embrace of the said guideway thereon, and means for moving said 55
- slug along said guideway to and leaving it temporarily immovable in a printing position, and for subsequently moving said slug away from said position and off said member. 70
16. The combination of a movable type-form-carrying member having a slug guideway which extends thereon in a direction relatively transverse to the direction in which said member moves, means for periodically depositing address slugs onto said member and into the embrace of said guideway, means for moving the slug along said guideway to and temporarily leaving it stationary in the required position relative to the part of said member on which the type-form may be secured, and for subsequently moving said slug along said guideway away from said position and off said member. 75
17. In a printing machine, the combination of a movable type supporting member having in its surface a slug guide-way which extends across the same to one edge thereof, a slug holder fixed above said member, means carried by said member for periodically withdrawing a slug from the holder, means for compelling said slug to move with the member, and means for moving the slug crosswise of the member in said guide-way to a printing position and then in the opposite direction across said member to the end of said guide-way. 80
18. The combination of a movable type carrying member, a slug holding hopper fixed above said member, means carried by 85 said member for periodically withdrawing from said hopper the lowest slug therein, a transversely movable propeller on said member adapted to engage with the slug so withdrawn and to move it crosswise of said type carrying member, means for moving said propeller, and means for automatically disengaging the same from the slug. 90
19. The combination of a member whereon is a guideway for supporting and guiding address slugs, a hopper adapted for containing a stack of address slugs, means for withdrawing said slugs serially from said hopper and depositing them in the embrace of said guideway, and means for moving 100 each of said slugs along said guideway to and temporarily leaving it in printing positions, and for subsequently moving it off of said member. 110
20. In a machine of the character described, the combination with means for carrying a form for the body of a letter and a removable address form, of two platens, and means whereby one cooperates with both the body and address and the other with the address only, whereby the machine may print addressed letters and corresponding envelopes. 115
21. In a machine of the character described, the combination with a rotating cy- 120

lindrical member adapted to carry a form for the body of the letter and a removable address form, of two platens and means whereby one platen coöperates with both the body and address, and the other with the address only, whereby the machine may print addressed letters and corresponding envelops.

22. In a machine of the character described, the combination of means for carrying a form for the body of the letter and a removable address form, of two rotary platens, and means whereby one coöperates with both the body and the address and the other with the address only, whereby the machine may print addressed letters, and corresponding envelops.

23. In a machine of the character de-

scribed, the combination with a rotary cylindrical member adapted to carry rows of 20 type with which to print the body of a letter, and a removable address plate, of two platens coöperating with the cylindrical member while rotating to print by rolling contact, and means whereby one platen coöperates 25 with both the body of the letter and the address plate and the other with the address plate only whereby the machine may print addressed letters and corresponding envelops.

In testimony whereof, I hereunto affix my 30 signature in the presence of two witnesses.

EDWARD G. ERNST.
